UNITED STATES PATENT OFFICE.

WILLIAM F. SMITH, OF BROOKLYN, NEW YORK, ASSIGNOR, BY MESNE ASSIGNMENTS,
TO WESTERN ELECTRIC COMPANY, INCORPORATED, A CORPORATION OF NEW YORK.

TWISTING-MACHINE.

1,247,462.

Specification of Letters Patent. Patented Nov. 20, 1917.

Application filed October 17, 1914. Serial No. 867,098.

To all whom it may concern:

Be it known that I, WILLIAM F. SMITH, a citizen of the United States, residing at Brooklyn, in the county of Kings and State of New York, have invented a certain new and useful Improvement in Twisting-Machines, of which the following is a full, clear, concise, and exact description.

This invention relates to twisting machines, and more particularly to machines for the twisting of strands for use in electric cables and like articles of manufacture.

The object of this invention is to provide a machine for rapidly and economically producing twisted strands of highly efficient electrical properties valuable in the formation of cables used for the electrical transmission of intelligence.

In accordance with this invention means is provided for equalizing the speed of the strands through a twisting machine and for causing them to be fed in a straight line to the twisting means whereby the length of the strands to be twisted will be maintained equal. The specific means provided for this purpose may comprise a plurality of wheels having grooves in their peripheries traversed by the conductors, some of said wheels being geared together.

This invention is illustrated in the accompanying drawings in which the same reference characters are used throughout to designate the same parts, and in which—

Figure 1 is a front elevation of a twisting machine embodying this invention;

Fig. 2 is a view in perspective of the length equalizing mechanism of the twisting machine shown in Fig. 1;

Fig. 3 is a view on line 3—3 of Fig. 4; 40 and

Fig. 4 is a view partly in section of the length equalizing mechanism shown in Fig. 2.

Referring to the drawings, 5 and 6 are side frame members joined at top and bottom respectively by supporting plates 7 and 8. Mounted upon the bottom supporting plate 8 is a revolving frame comprising a shaft 9 carrying a bar 10 upon each end of which is mounted a yoke 11. Mounted upon the upper end of the shaft 9 and hollow hubs 12, 12 of the yokes 11, 11 is a cross bar 13, upon which is mounted an auxiliary frame, the upper end thereof being hollow and journaled in the upper supporting plate

7. The housing 15 contains the usual gears for driving a capstan 16 for drawing the conductors through the revolving frame, said gears meshing with a gear on the upper end of the auxiliary frame 14. Since the arrangement of the gears for driving the capstan from the frame 14 is well known, it is not considered necessary to either show or describe them. The revolving frame is driven through the necessary shafting and gears from a suitable motor, such as is shown at 20 in Fig. 1.

In order that the twisted conductors may be properly wound on a receiving reel, there are provided pedestals 21 and 22 in which is journaled a shaft 23 which carries a reel 24 and is driven by means of a belt 26 passing over a pulley 25 carried by said shaft and over a pulley 27 carried by a shaft 28 between the motor 20 and the revolving frame.

To provide for the proper distribution of the twisted conductors on the receiving reel, a distributor screw 29 is journaled in the upper ends of the pedestals 21 and 22. The distributor screw 29 carries a distributor block 30 which guides the twisted conductors, and is driven by means of a belt 31 passing over pulleys 32 and 33 carried by the shaft 23 and the distributor screw 29, respectively.

To make the two conductors travel at the same rate of speed through the twisting machines, the auxiliary frame consists of an upper portion 40 having two legs 41 and 42, and two side plates 43 and 44, the lower ends of which are suitably secured to the cross bar 13, and the upper ends to the legs 41 and 42, respectively. A spacer 45 and a bolt 46 serve to hold the plates 43 and 44 rigid. Each of two wheels 50, 50 provided with a plurality of V-shaped grooves 51 on the periphery thereof, are secured to a bevel gear 52 loosely mounted through the medium of ball bearings 54 on a shaft 53 secured to the plates 43 and 44. The bevel gears 52, 52 mesh with pinions 55, 55 carried by a spider 56 mounted on the shaft 53. The two other wheels 60, 60 provided with a plurality of V-shaped grooves 61 on the periphery thereof, are loosely mounted, through the medium of ball bearings 62, upon a shaft 63 secured to the plates 43 and 44.

Immediately above the speed equalizing

mechanism, a grooved guide 70 provided with two spiral grooves 71, 71 is mounted in a chuck 72 supported by a block 69 suitably held between the legs 41 and 42. The 5 chuck 72 is provided with two diagonally arranged openings 73, 73 for the passage of the conductors to be twisted. The lower end of the grooved guide 70 is provided with a slot 74, into which fits a key 75 for locking 10 the grooved guide 70 in the chuck 72, the block 69 also being provided with a slot 76 registering with the slot 74, into which said key fits to lock the chuck 72 and block 69 together. 15 Referring now to the operation of twisting machine embodying the invention hereinbefore described and illustrated in the accompanying drawings, the spools containing the conductors to be twisted are mounted 20 in a horizontal position in the yokes 11, 11 as shown in Fig. 1. The conductor 80 from the spool mounted in the yoke 11 at the left of the machine, is led up through the hollow hub 12 thereof (see Fig. 2) up the wheel 50 25 (on the right) in the outer V-shaped groove thereof, down and under the wheel 60 (on the right) in the outer V-shaped groove thereof, up and over said wheel 50 in the next groove thereof (this cycle may be repeated until the grooves of the wheels 50 and 60 are each traversed by the conductor 80), then passing from the groove of said 30 wheel 50, through one of the openings 73, through one of the spiral grooves 71 of the 35 grooved guide 70, at the upper end of which conductor 80 is joined by the other conductor 81, which has followed a similar course from the reel on the right of the machine through the grooves of the wheels 50 and 60 40 on the left.

As the two conductors pass through the spiral grooves 71, 71 of the grooved guide 70, there is formed in each a definite spiral corresponding to the length of lay of the twist 45 and the pitch of the groove. The pitch of both grooves is always made equal to the length of the twist desired in the twisted strands. From the upper end of the grooved guide 70, the two conductors pass through 50 the hollow end of the upper portion 40 of the auxiliary frame, around the capstan 16 several times, and finally onto the receiving reel 24. When the machine is started, the revolving frame, wheels 50, 50 and 60, 60 55 begin to revolve, the wheels 50, 50 and 60, 60 being driven by the conductors which traverse the V-shaped grooves thereof. The action of the conductors in traversing the grooves of the wheels 50, 50 and 60, 60 60 causes the equalization of the speed of the conductors through the mechanism.

It has been determined that the action of twisting the conductors in machines in which flat-rimmed wheels are used for equalizing 65 the speed of the conductors, causes the con-

ductors to take a serpentine path of the periphery of these wheels, thereby impairing the length equalizing effect of the wheels. By the use of wheels of this invention in the periphery of which there are V-shaped 70 grooves, and having some of said grooved wheels geared together, the conductors are maintained in a definite position on the wheels, and are fed in a straight line to the twisting means, thereby overcoming the difficulties experienced with the flat-rimmed wheels and causing the twisted conductors to be of equal length. The V-shape of the grooves prevents the slipping of the conductors on the wheels. 75

What is claimed is:

1. In a strand twisting machine, a support, a plurality of sets of grooved wheels mounted upon said support, the wheels of one of said sets being mounted on the same 80 shaft and geared together to rotate at the same speed, the wheels of the other set being independently rotatable and co-operating with the wheels of the first set, and means for drawing off the twisted strands 85 each strand passing around one of said grooved wheels of each of said sets for equalizing the speed thereof. 90

2. In a strand twisting machine, a support, a plurality of sets of grooved wheels 95 mounted upon said support, the wheels of one of said sets being geared together to rotate at the same speed but in opposite directions to each other, the wheels of the other set being rotatable independently of each 100 other, and a plurality of strands, each passing over one wheel of each set for equalizing the speed of said strands. 100

3. A support, a plurality of grooved wheels mounted on said support, said wheels 105 being free to rotate independently of each other, another plurality of grooved wheels geared together and mounted on said support, and a plurality of strands, each strand passing over one wheel of each of said sets 110 for imparting a uniform movement to said strands. 110

4. In a machine for twisting strands, a revolute frame, a plurality of grooved wheels mounted upon said frame and geared 115 together to rotate in reverse directions, said wheels being caused to rotate by the frictional engagement of the strands passing thereover, and a plurality of grooved wheels also mounted upon said frame and co-operating with said geared wheels for equalizing the speed of the strands. 120

5. In a machine for twisting strands, a revolute frame, an auxiliary frame carried by said revolute frame, a plurality of 125 wheels carried by said auxiliary frame, said wheels being geared together, and a plurality of wheels also carried by said auxiliary frame, said wheels being mounted on the same shaft and co-operating with said 130

first mentioned wheels for equalizing the speed of the strands.

6. In a machine for twisting strands, a revolute frame, a plurality of spool supports carried thereby, means for drawing off the twisted strands, a plurality of grooved wheels geared together, and a plurality of independently revolute wheels, each strand passing around one of said grooved wheels and one of said independently revolute wheels for equalizing the speed thereof.

7. In a machine of the character described a revolving frame for twisting a plurality of strands, means for drawing the strands through said frame, and means for equalizing the speed of the strands comprising an

auxiliary frame mounted upon said revolving frame, two wheels mounted in said auxiliary frame, said wheels having V-shaped grooves in the periphery thereof and being geared together and two other wheels having V-shaped grooves in the periphery thereof mounted in said auxiliary frame, each strand traversing the grooves of one of said geared wheels and one of said second-mentioned wheels.

In witness whereof, I hereunto subscribe my name this 16th day of October, A. D. 1914.

WILLIAM F. SMITH.
